UNITED STATES PATENT OFFICE

99,589

DESIGN FOR A LAMP

Ruth Strauss, New York, N. Y.

Application February 17, 1936, Serial No. 61,211

Term of patent 3½ years

To all whom it may concern:

Be it known that I, Ruth Strauss, a citizen of the United States, residing at New York, in the county of New York and State of New York, have invented a new, original, and ornamental Design for a Lamp, of which the following is a specification, reference being had to the accompanying drawing, forming part thereof.

The drawing is not lined to indicate any particular color but merely to bring out a contrast of color. The dominant feature of my design resides in the part shown in solid lines.

I claim:

The ornamental design for a lamp, as shown and described.

RUTH STRAUSS.
